BASEBALL GAME

William Pringle, Rego Park, Long Island, N. Y.

Application June 12, 1944, Serial No. 539,878

3 Claims. (Cl. 273—93)

The invention herein disclosed relates to game apparatus and particularly to apparatus for playing the game of baseball.

Objects of the invention are to provide a game which will simulate, so far as possible, all the plays of the regular game and will afford the players a real contest, such as that between the pitcher and the batter in the usual game.

Further special objects of the invention are to make the action as interesting and as realistic as possible, for example to enable either right handed or left handed players to apply their respective skills in their own particular ways and to accomplish this without having to alter the structure, thus simulating the effect of a right or left handed batter stepping up to the plate or a right or left handed pitcher taking his position in the box.

Other objects are to accomplish all the above within a reasonably simple and inexpensive form of construction, of attractive appearance and generally desirable in other ways.

The foregoing and other desirable objects are attained by the novel features of construction, combinations and relations of parts hereinafter described, illustrated by way of example in the accompanying drawing and broadly covered in the claims.

In the drawing, there is shown a practical and at present preferred embodiment of the invention, but structure may be modified and changed in various ways, all within the true intent and broad scope of the invention as hereinafter defined and claimed.

Fig. 1 in the drawing is a plan view showing the parts in the position they may occupy at the start of a play;

Fig. 2 is a similar view illustrating the parts as they may stand at the completion of a play;

Fig. 3 is a top view of the parts as in Fig. 1, with the cover or playing board portion of the device removed;

Fig. 4 is an enlarged longitudinal sectional view as on substantially the plane of line 4—4 of Fig. 1;

Fig. 5 is a broken transverse sectional view as on substantially the plane of line 5—5 of Fig. 1; and

Figs. 6 and 7 are detached detail views of the wedge slide element and the handle representing the batter.

The playing board 10, as shown in Figs. 1 and 2, is laid out to represent a baseball field, with bases and with positions for the batter and the pitcher.

For purposes of making the game more realistic

the pitcher is represented by a ball 11 and the batter by a knob or handle 12 carrying a bat 13.

The plays are represented by the designations 14 disposed in the radial segments of a disc or spinner 15. This disc is shown as having a hub 16 rotatably and slidably journaled on a stud 17. The ball 11 is shown as engaged over the end of the spindle 18 forming the upper end of the hub.

The stud 17 is shown as supported by a back board 19 secured to the front board 10 about the edges, with an intervening spacer 20 to provide a chamber 21 for the indicating dial and other parts.

The front board has a window 22 through which the individual designations on the dial may be seen.

The knob 12, representative of the batter, is pivotally mounted on a stud 23 carried by the back board and is shown as having a squared or angular cross section inner end portion 24 engageable in a correspondingly shaped opening 25 in a double ended shutter having oppositely extended blades 26, 27 to pass beneath and close the window 22, according to which way the bat is swung.

At the center the shutter carries a radially projecting arm 28 disposed substantially at a right angle to the two oppositely projecting shutter blades. A pivot pin 29 on this arm provides the connection with a link 30 which carries an inclined brake shoe 31 for engaging beneath and stopping the rotation of the dial. This brake shoe carrying link is shown as slidingly guided at its free end by having the longitudinally slotted portion 32 of the same engaged about a free turning

roller 33 on the dial pivot stud 17. The throw of the shutter arm 28, as represented by the distance between pivot centers 23 and 29, is sufficient to carry the brake shoe from a position clear of the disc, as in Figs. 1, 3 and 4, into full holding engagement with the disc regardless of which way the batter element is swung, that is, in a counter-clockwise direction from the Fig. 1 position, as for a right handed batter, or in a clockwise direction, starting with the bat at the left hand side, Fig. 1, as would be the case for a left handed batter.

For easy scoring purposes, as for showing "strikes," "balls," "outs" and "runs" a series of pointers and suitable markings may be located at one end of the board substantially as indicated at 34, 35, 36 and 37.

A washer 38 engaged over the pivot stud 23, Fig. 5, supports the arm 28 of the shutter at the proper level to keep the pivoted end of the brake link 30 from dragging over the face of the back board.

Stops may be provided to locate the starting positions of the bat at either the left or the right hand side, said stops being here provided by a single ridge or bar 39 disposed to be engaged by the shutter arm 28 at the limit of its back swing in the opposite directions.

To visualize the plays more definitely, tokens such as shown at 40, representing the men in play, may be shifted about on the board as the game progresses.

The game may be played by one, two, or any number of players, but usually by two players, one acting as the pitcher and, in effect, throwing the ball by spinning the knob 11 at the pitcher's position, and the other swinging the bat, when the ball is pitched, to stop the dial, thus in effect intercepting the thrown ball and to uncover the window and show what play has been accomplished.

A right handed pitcher may spin the dial in a clockwise direction and a left handed pitcher may turn the dial in the opposite direction. The same as to the batter, a right handed person may choose to swing the bat right handedly and a left handed person may choose to strike left handedly, as he would in playing the regular game. These differences in play are accomplished without shifting or changing any parts and the covering and uncovering of the window and the releasing and stopping of the spinner are in every case effected just the same. These various possibilities give the game constant interest and enable players to choose which way they will play and, if desired, to change their mode of play, at the end of or right in the midst of a game, features which may be governed by rules that may be adopted.

With two players, usually the "batter" will take a position at one end of the board and the "pitcher" a position at the opposite end of the board, and the scores may be set up on the indicators 34, 35, 36, 37 by either one or both the players.

The complete game board may be inexpensively made up of simply two layers of plywood at 10, 19, with spacing strips 20 secured between the edge portions of the same. The shutter may be a thin piece of sheet material fastened on a wooden piece forming the lever 28. While not so restricted, the designations arranged in the order illustrated in Fig. 3 are preferred since these have been found to give all desirable opportunities of play.

What is claimed is:

1. A baseball game comprising a board laid out in representation of a baseball field, a batter simulating element pivotally mounted at the home plate position on the board and mounted free to swing in opposite directions to simulate the action of either a right-handed or a left-

handed player, a spinner rotatably mounted at the pitcher's plate position on the board and carrying designations of different plays of the game, said spinner being mounted to turn beneath the board and the board having a window to expose only a single designation at a time, a shutter for closing the window over said designations on the spinner and connected with the rotatably mounted batter simulating element to close said window when the batter simulating element is turned back to either right-handed or left-handed batting positions and to open the window when the batter simulating element is turned to simulate batting from either a right-handed or a left-handed position, and means also connected with said batter simulating element for effecting stoppage of the spinner approximately at the moment of the shutter opening the window from travel in either of said right-handed or left-handed positions.

2. Game apparatus comprising a spinner provided with play designating indications, a shutter mounted for covering and uncovering said designations, a player simulating member mounted for movements simulating the movements of a player drawing back and swinging at a ball, means for arresting rotation of the spinner and connections from said player simulating member for effecting freeing of said arresting member from the spinner and covering of the designations by the shutter when the player simulating member is shifted in the drawing back direction and for effecting coaction of the arresting means with the spinner and uncovering movement of the shutter when the player simulating member is shifted in the direction simulating the movement of a player swinging at a ball.

3. A baseball game comprising a game board having the representation of a baseball field, a spinner journaled at the pitcher's plate and carrying designations of play, a window on the board for exposing the play designations one at a time, a shutter movable to cover and uncover said window, a player simulating member mounted at the home plate position and having movement to simulate the movements of a player drawing back and swinging at a ball, spinner arresting means and connections between said player simulating member and said shutter and arresting means for freeing the arresting means from the spinner and moving the shutter in the window uncovering direction upon shifting of the player simulating member in the direction simulating the drawing back movement of a player and for effecting engagement of the arresting means with the spinner and the window uncovering movement of the shutter in the shifting of the player simulating member in the direction simulating that of a player swinging at a ball.
